DRYING AND IRONING MACHINES

Henri Léon Lucien Jesus, 77 Rue de Bellevue,
Boulogne-Billancourt, France
Filed June 28, 1961, Ser. No. 120,245
Claims priority, application France, June 30, 1960,
831,601, Patent 1,269,278
6 Claims. (Cl. 38—56)

The present invention relates to ironing machines of a known type comprising at least two work units, that is to say one heated unit and one application unit for drying and ironing linen pieces which pass between these two units.

It is known that this type of machinery is constructed in a number of rather different sizes, thus making it necessary for the manufacturers of this kind of equipment, who wish to offer to their customers a certain range of equipment manufactured by them, to keep as complete a stock as possible of the work units, that is to say cylinders and cups or troughs, of these machines. Such a stock obviously has the disadvantage of necessitating a fairly substantial immobilization of capital.

To overcome the above-mentioned disadvantage drying and ironing machines have been conceived for limiting stock to individual standardized elements so that, depending on the size of machines required by users, the manufacturer can, for each machine, produce each of the aforementioned work units by means of a simple assembly of standardized elements in a suitable number according to the width which, in each specific case, the heating element or elements of the said machine are designed to have.

To this end, at least one of the work units of a drying and ironing machine either comprises one standardized hollow section or is formed by the assembly, in the direction of the width of the machine, that is to say parallel to the axis of rotation of the cylinder, of juxtaposed identical standardized hollow sections of small width in the direction considered, each of said sections being provided with an ironing surface, heating means, suction means, etc., which characterize the work unit. The section or each of said sections comprises two coupling end-plates, each of which is provided with assembly means for the purpose of joining the said standardized section either to an adjacent section or to supporting brackets.

The present invention has for its object to simplify the heating circuit of one or each section of the working unit of a drying and ironing machine.

To this end, the heating conduit of one or each section advantageously comprises a series of heating ducts each formed by a portion of the wall of the section and by a strip of angle iron having the longitudinal edge of each of its two flanges welded against the rear surface of said wall portion the outer surface of which forms the working surface of the unit.

The individual heating ducts are advantageously arranged parallel to the axis of the machine and their ends are so interconnected that the entire duct runs zigzaggedly.

Each interconnection, or return, between adjacent ducts is constituted, near the corresponding end plate of the section, by an inclined trapezoid shaped plate, the parallel edges of said trapezoid plate being welded respectively to the wall of the section and to the end plate of said section, whereas the sides of said trapezoid plate are welded to the facing flanges of the two adjacent strips of angle-iron to be interconnected, said flanges having been obliquely cut away.

Each heating conduit can be heat-insulated, for example in the form of a heat-insulating coating placed on the external surface of the angle iron.

2

The description which follows below relates to an example of construction of a heating trough or cup improved in accordance with the said invention, the said example being given solely by way of indication without implied limitation and illustrated diagrammatically in the accompanying drawings, in which:

FIG. 1 is a schematic view in transverse cross-section at right angles to the axis of the cylinder of a drying and ironing machine having an ironing cylinder which is intended to cooperate with a cup or trough made of two standardized hollow sections.

FIG. 2 is a developed view of a portion of a trough element, the wall of which is provided with the working surface being assumed to have been removed for the purpose of showing the arrangement of the zig-zag heating conduit.

FIG. 3 is a view in cross-section taken along the line III—III of FIG. 2;

FIG. 4 is a view in cross-section on a larger scale of a portion of a trough element with heat-insulated heating conduit;

FIG. 5 is a developed view of the trough formed by two standardized hollow sections of which the wall comprising the working surface has been removed;

FIG. 6 is a view in cross-section taken along the line VI—VI of FIG. 5.

FIG. 7 shows a part of the cylindrically-shaped section of the trough shown in FIGS. 1 and 3 of the drawing;

FIG. 8 illustrates how the flanges of the angle-iron strip are obliquely, i.e., at a bias, cut away at the ends of said strip;

FIG. 9 illustrates schematically the zigzagging path of the entire conduit, according to the invention;

FIG. 10 is a detail section showing the suction holes between adjacent conduits.

FIG. 11 shows in sectional detail a portion of the concave walls joined by an end plate.

FIG. 12 illustrates the arrangement of the ducts formed by the angle-iron strips; and

FIG. 13 shows a trapezoidal end plate welded to a concave wall embodied in the invention.

In the example of construction which has been illustrated in the drawings, each standardized section of a heating trough having a concave working face comprises a concave wall 1 on which is formed a machined, or polished, outer surface with which is intended to cooperate a cylinder C and a convex wall 2 which is coupled to the wall 1 by end wall-members 3 and 4. Two end-plates 5 and 6 which are coupled to the walls 1, 2, 3 and 4, close the section which constitutes the standardized element.

On the internal surface of the wall 1 are welded the longitudinal edges of the flanges 7 which form an angle-iron strip 7a. Each angle-iron-strip 7a constitutes, together with the portion of the corresponding internal surface of the wall 1, part 8 of a zig-zag heating conduit.

When the convex portion of the trough is also employed, the wall 2 can also comprise a heating system which is similar to the system associated with the wall 1 and illustrated in dotted lines in FIG. 1.

Each of the returns, or junctions, between the rectilinear parts 8 of the heating conduit is formed by an oblique cut away, at 9, symmetrically with respect to each other, of the oppositely facing flanges 7 of two adjacent strips of angle-iron, and by welding on said obliquely cut-away flanges an inclined plate 10 having the shape of a trapezoid, the bases of which are welded to the wall 1 and to the corresponding end-plate (5 or 6) and the sides of which are welded, at 9, to the flanges referred-to above.

The flanges 7 of the strips 7a can, if necessary, be heat-insulated by means of an insulating coating 11, as shown

in FIG. 4, which prevents the loss of heat in the interior of the standardized element.

In the example of FIG. 5, each standardized element comprises two symmetrical heating conduits, each having its admission 12 and a common outlet 13.

In FIGS. 5 and 6, it can be seen that the two standardized trough elements are coupled to each other with their end-plates 5 back to back by means of bolts 14, while the end-plates 6 are coupled to right-angle supporting brackets 15.

Between the rectilinear parts of the heating conduits, the working wall 1 is provided with holes 16 intended for the suction of the steam given off by the linen pieces which pass between the cylinder and the heating trough, the interior of each standardized element being in communication through orifices 17 as shown in FIG. 1, with suction means which have not been illustrated in the accompanying drawings.

As illustrated clearly in FIG. 8, individual angle-iron strips are cut at both ends in such a manner that at one end, one of the flanges 7 is obliquely cut, whereas at the other end, the other flange 7 is cut, so that by way of the trapezoidal end plates eventually a zigzag path is established extending over the cylindrically-shaped area of the section. FIG. 10 is an enlarged portion of the schematic side view of FIG. 1, in which optional heat insulation on the outside of the angle-iron strips is shown, as well as a second row of conduits of the other wall interlaced with the first row.

What I claim is:

1. In a drying and ironing machine having at least two work units including a rotatable cylinder and a fixed trough adapted to cooperate with said cylinder, at least one of said units comprising at least one hollow section provided with two end plates and a cylindrically-shaped wall having an external working surface and fitted with duct means for heating purposes, said means comprising at least one conduit, said conduit being formed by a portion of said cylindrically-shaped wall and a strip of angle iron whose two flanges have their longitudinal edges welded against the internal surface of said wall.

2. In a drying and ironing machine having at least two work units including a rotatable cylinder and a fixed trough adapted to cooperate with said cylinder, at least

one of said units comprising at least one hollow section provided with two end plates and a cylindrically-shaped wall having an external working surface and fitted with duct means for heating purposes, said means comprising at least one conduit, said conduit being formed by a plurality of straight conduit parts parallel with the axis of said cylinder and each one of said conduit parts being formed by a portion of said cylindrically-shaped wall and a strip of angle iron whose two flanges have their longitudinal edges welded against the internal surface of said wall.

5 3. A drying and ironing machine as claimed in claim 2, wherein two adjacent straight conduit parts are connected by means of a duct part made of an inclined trapezoidal plate the bases of which are welded respectively against one end plate and against the internal surface of the cylindrically-shaped wall, the lateral edges of said trapezoidal plate being welded to the facing flanges of the adjacent angle-iron strips, the extremities of which 15 are cut to meet with the lateral edges of the said trapezoidal plate.

15 4. A drying and ironing machine as claimed in claim 1, further comprising a heat-insulation applied on said angle-iron strip.

20 5. A drying and ironing machine as claimed in claim 2, wherein said straight conduit parts are connected alternately at their ends by means of duct parts, providing a zig-zag heating conduit.

25 6. A drying and ironing machine as claimed in claim 2, wherein said cylindrically-shaped wall of said unit is pierced, between said straight conduit parts, with holes for communicating the interior of said hollow section with the working surface, at least one of said end plates being pierced with a hole for connecting said interior with suction means.
